(57) **CLAIM**

The ornamental design for a laptop computer, as shown and described.

DESCRIPTION

FIG. 1 is a perspective view of a laptop computer, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a top perspective view thereof, in an alternative position; and,

FIG. 9 is a bottom perspective view thereof, in the alternative position.

The broken lines illustrating portions of the laptop computer form no part of the claimed design.
